UNITED STATES PATENT OFFICE.

EMILIO ALTIERI, OF NEW YORK, N. Y.

SHOE LAST.

Application filed December 16, 1922. Serial No. 607,280.

This invention relates to shoe lasts and has for one of its objects to provide a last upon which a shoe may be built which will correctly conform to the shape of a normal human foot, not only the upper part of the foot but the lower portion as well.

Other objects are to provide a correctly designed last which may be employed in making comfortable, correctly constructed 10 shoes of the materials heretofore commonly employed or, preferably, to obtain the maximum beneficial results, having insoles such as that disclosed and claimed in my Patent No. 1,434,471. Other objects and advantages will appear as the invention is herein- 16 after disclosed.

Referring to the drawings, which illustrate what I now consider a preferred form of the last embodying my invention;—

20 Fig. 1 is an elevation of a last adapted to be employed in constructing shoes adapted to be worn by females, a heel (forming no part of the last) being shown in dotted lines to facilitate explanation of the invention.

25 Fig. 2 is a top plan view of the last shown in Fig. 1.

Fig. 3 is an inverted plan view of the last shown in Fig. 1, the dotted lines indicating the outline of a reinforcing member that 30 may be employed in the shoe under construction.

Fig. 4 is a sectional elevation taken substantially on the plane of the line 4—4 of Fig. 3.

35 Figs. 5, 6 and 7 are sections taken on the planes of the lines 5—5, 6—6 and 7—7, respectively, of Fig. 3, Figs. 5, 6 and 7 being upright and not inverted views.

The last illustrated is one adapted to be 40 employed in the construction of a shoe adapted to be worn on the left foot of a woman. It will be obvious that a generally similar last may be employed for constructing shoes for the right foot and that

45 other sizes of suitably shaped lasts may be employed for constructing shoes intended for human beings of various ages and sexes, without departing from the scope of the invention as defined in the appended claims.

50 The last illustrated is constructed of wood or other suitable material and, in order to facilitate its removal from a built up shoe, is preferably constructed of two members 10, 11, detachably connected by means of a screw 12. A dowel pin 14 may be provided

55 socket 13 in the member 11, these elements together with the screw 12 serving to hold the parts 10, 11, in correct assembled position. The last illustrated in the drawings 60 differs from the lasts heretofore employed, particularly in the following respects.

The sole is so shaped as to rest substantially flat, from tip to arch, when the heel 16 (a part of the shoe and not of the last) 65 is in position under the heel of the last. It will further be noted that the instep portion 17 of the last is full or rounded out (see Fig. 1) instead of being in the form of a more or less sharp angle. The heel portion of the last is formed with a projecting or raised portion 18 which may either be an integral part of the member 10 or may be constructed of leather or other suitable material and glued, cemented or otherwise secured to the last. The raised portion 18 is designed to be of substantially the same configuration as the lower part of the heel bone, or oscalcis, of a human foot. The under-arched portion of the last is shaped substantially as indicated in Figs. 4 to 7, i. e., it is longitudinally arched or convexed upwardly between the heel and the section 5—5 (corresponding to junctions of the metatarsal bones with the toes of the human foot) and transversely arched upwardly at and between the sections 5—5 and 6—6, this transverse arch diminishing toward, and substantially disappearing at, the section 7—7. In short, the under surface of the heel and instep or arched portion of the last is of such configuration as to form a snug fit with a reinforcing plate shown in dotted lines at 16' in Fig. 3 of the drawings of the present application, and shown in Fig. 5 of my Patent No. 1,434,471. 95 That portion of the lower surface of the last which extends between the section 5—5 and the tip is substantially a plane surface except for the raised portions 19, 20, 21, 22 which I shall now describe.

100 The portion 19 is a raised portion, either integral with the member 10, or separately formed of leather or other suitable material and glued or cemented or otherwise secured to the member 10, and so shaped as to simulate the lower part of the outer phalange of the great toe of a human foot. The raised portions 20, 21, 22 are similarly formed but are of such configuration as to simulate the lower portions of the ball, the joint between the fifth metatarsal and the smallest toe, and the joint between the first metatarsal and

110 on the member 10 and adapted to enter a

the great toe, respectively, of the human foot.

It will now be appreciated that I have provided a last which simulates the shape of a human foot, and particularly the lower portion or foundation thereof. When a shoe is built up on this last it is caused to assume a shape complementary to that of the last so that the foot of a wearer of such a shoe 10 will be properly and comfortably supported. The insole of such a shoe will have depressions, corresponding to the projections 18 to 21 of the last, these depressions being adapted to receive and conform to the heel 15 bone or os calcis, the outer phalange of the great toe, the ball, the joint between the fifth metatarsal and the smallest toe, and the joint between the first metatarsal and the great toe, respectively, of the normal human 20 foot. If desirable these depressions in the insole of the shoe may be provided with pads or cushions of any suitable soft material. The last disclosed may also be, and preferably is, employed in the construction 25 of insoles such as those disclosed in my above mentioned patent.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried 30 out by other means. Also, while it is designed to use the various features and elements in the combinations and relations described, some of these may be altered and others omitted and some of the features of 35 each modification may be embodied in the others without interfering with the more general results outlined, and the invention 40 extends to such use.

What I claim is:—

- 45 1. A shoe last comprising a body member having a projection on the sole portion of substantially the same shape as the lower portion of the ball of a human foot.
- 50 2. A shoe last comprising a body member having a projection at the heel portion of substantially the same shape as the lower portion of the os calcis of a human foot, and a projection on the sole portion of substantially the same shape as the lower portion 55 of the ball of a human foot.
- 55 3. A shoe last comprising a body member having a projection at the heel portion of substantially the same shape as the lower

portion of the os calcis of a human foot, a projection on the sole portion of substantially the same shape as the lower portion of the ball of a human foot, a projection on the sole portion of substantially the same shape as the lower portion of the joint between the first metatarsal bone and great toe of a human foot, and a projection on the sole portion of substantially the same shape as the lower portion of the joint between the fifth metatarsal and the smallest toe of a human foot. 60 65 70

4. A shoe last comprising a body member having a projection at the heel portion of substantially the same shape as the lower portion of the os calcis of a human foot, a projection on the sole portion of substantially the same shape as the lower portion of the ball of a human foot, a projection on the sole portion of substantially the same shape as the lower portion of the joint between the first metatarsal bone and great toe of a human foot, a projection on the sole portion of substantially the same shape as the lower portion of the joint between the fifth metatarsal and the smallest toe of a human foot, and a projection on the sole portion of substantially the same shape as the lower portion of the outer phalange of the great toe of a human foot. 80 85 90

5. A shoe last as set forth in claim 1 and whose body member is provided with a longitudinally upwardly curved and transversely upwardly curved arch extending from adjacent the heel substantially to the sole portion proper. 95

6. A shoe last as set forth in claim 2 and whose body member is provided with a longitudinally upwardly curved and transversely upwardly curved arch extending from adjacent the heel substantially to the sole portion proper. 100

7. A shoe last as set forth in claim 3 and whose body member is provided with a longitudinally upwardly curved and transversely upwardly curved arch extending from adjacent the heel substantially to the sole portion proper. 105

8. A shoe last as set forth in claim 4 and whose body member is provided with a longitudinally upwardly curved and transversely upwardly curved arch extending from adjacent the heel substantially to the sole portion proper. 110

In testimony whereof I hereto affix my signature.

EMILIO ALTIERI.
